FIG.1

FIG.2

FIG. 3

FIG. 4

FIG. 5

FIG. 1 is a perspective view of a target trap showing my new design, the trap being in a cocked position.

FIG. 2 is a top plan view thereof.

FIG. 3 is a side elevational view thereof.

FIG. 4 is a front elevational view thereof.

FIG. 5 is a rear elevational view thereof.

The spring is fragmentarily shown in FIGS. 1 and 3 for convenience of illustration, it being understood that the spring is continuous along the area indicated by the broken lines.

I claim:

The ornamental design for a target trap, substantially as shown and described.
